(57) **CLAIM**

The ornamental design for a pair of automobile grille extinctions, as shown and described.

DESCRIPTION

FIG. 1 is a front perspective view of a pair of automobile grille extinctions showing my new design in accordance to a right side embodiment;

FIG. 2 is a front perspective view of a mirrored configuration of the pair of automobile grille extinctions in accordance to a left side embodiment;

FIG. 3 is a front elevation view of the design in FIG. 1;

FIG. 4 is a rear elevation view of the design in FIG. 1;

FIG. 5 is a right side elevation view of the design in FIG. 1;

FIG. 6 is a left side elevation view of the design in FIG. 1;

FIG. 7 is a top plan view of the design in FIG. 1;

FIG. 8 is a bottom plan view of the design in FIG. 1; and,

FIG. 9 is a front perspective view of an exemplary automobile with the right side embodiment of the pair of automobile grille extinctions installed.

It is understood that the left side embodiment of the pair of automobile grille extinctions is also represented by the mirrored configurations illustrated between FIGS. 3-8.

The broken line showing of an automobile is provided for the purpose of illustrating environmental structure and forms no part of the claimed design.
